UNITED STATES PATENT OFFICE.

DAVID W. BENTON, OF CLAY, WEST VIRGINIA.

PEN-RACK.

1,293,002.

Specification of Letters Patent.

Patented Feb. 4, 1919.

Application filed November 5, 1918. Serial No. 261,242.

To all whom it may concern:

Be it known that I, DAVID W. BENTON, a citizen of the United States, and resident of Clay, in the county of Clay and State of West Virginia, have invented certain new and useful Improvements in Pen-Racks, of which the following is a specification.

This invention relates to a pen rack and more particularly to a pen rack embodying attaching means whereby the rack may be supported from an ordinary bottle or well, an object of the invention being to provide a pen rack comprising a plurality of resilient coils of wire adapted to engage between two adjacent coils a pen holder or like article for supporting the same, and also to provide means connected to the supporting base of the pen rack for detachably connecting the pen rack to an ink bottle, ink well or the like, whereby the pens may be supported in close proximity to the supply of ink and also to provide a pen rack structure which is comparatively simple in construction and easy to manufacture.

Another object of the invention is to provide an attaching structure for the pen rack which is adjustable, for fitting articles of various sizes and which is so constructed that two of the racks may be connected thereby and also attached to a support, such as an ink well.

Other objects of the invention will appear in the following detailed description, taken in connection with the accompanying drawing, forming a part of this specification, and in which drawing:

Figure 1 is a perspective view of the improved pen rack or holder showing the same attached to an ordinary ink bottle.

Fig. 2 is a plan of the pen rack or holder showing the portion of the bottle neck to which it is attached in section.

Fig. 3 is an enlarged fragmentary side elevation of the pen rack and its attaching means, and

Fig. 4 is a plan view of a pair of the pen racks connected and attached to an ink well.

Referring more particularly to the drawings wherein like characters indicate like and corresponding parts throughout the several views, A indicates an ordinary bottle, having a neck B and the improved pen rack generically indicated by the numeral 1 comprises the supporting bar or body 2 which carries a plurality of coils of resilient wire, the said coils having their lowermost por-

tions soldered to the supporting bar 2 as shown at 4. The wire of which coils 3 are formed has its outer end returned through the center of the coils and twisted with its inner end as shown at 5, the said twisted portion being suitably connected to or engaging the inner leg or side 6 of the substantially U-shaped portion 7 of the body or supporting bar 2. A pen holder is supported by insertion between a pair of the adjacent coils 3 as shown in Fig. 1 of the drawings.

The upstanding inner side 6 of the looped portion 7 has an attaching structure 8 connected thereto in any suitable manner, such as by soldering. This attaching structure comprises a strip of flexible metal which has one end bent upon itself to secure an eye 9 thereto. In attaching the pen rack to the neck B of the ink bottle A, the end which is normally free from connection with the eye or ring 9, is, after the flexible strip of metal has been passed about the neck of the body, as clearly shown in Fig. 2, looped through the eye or ring 9 as shown at 10 and folded back upon the portion thereof which engages the bottle neck, being confined and held in flat facial engagement with the outer surface of a portion of the bottle neck engaging portion of the flexible strip by suitable elastic or flexible rings 11. It will be noted that a plurality of these elastic or flexible rings 11 are mounted upon the attaching band 8 and that they engage against the neck of the bottle preventing rotary movement of the band about the bottle, owing to the frictional engagement between these elastic or flexible rings and the bottle neck. The rings 11 are preferably constructed of rubber.

When it is desired to attach two of the improved pen racks, to a relatively large ink well as shown in Fig. 4 of the drawing, the free end 10 of one of the flexible strips 8 is passed through the ring or eye 9 upon a second flexible attaching band or strip and is then folded back upon itself, and confined by means of one of the elastic or flexible rings 11, thereby connecting two of the attaching bands or strips 8 to form substantially a continuous ring, the length of which will be sufficient to extend about the ink well or other article indicated at C, after which the free end 10 of the remaining attaching band or strip is passed through the eye or ring 9 of the first band or strip and folded back upon itself, being confined by one of the

flexible rings 11 to securely bind the connected attaching band or strip about the ink well. In Fig. 4 of the drawings, the two pen racks 1 are positioned diametrically opposite each other, but it is to be understood that they may be positioned in practically any desired relation to each other by varying the turned over length 10 of the first band 8, which is connected to the second band 8 prior to the mounting of the bands about the ink well.

Changes in details may be made without departing from the spirit of this invention, but;

15 I claim:

1. The combination with an ordinary ink receptacle, of a pen rack, a supporting bar for said pen rack, a flexible attaching band connected to one end of said supporting bar, 20 a ring carried by one end of said band and adapted to receive the other end of the band therethrough whereby the band may be drawn tightly about said ink receptacle for supporting the pen rack therefrom, and a 25 resilient friction ring mounted about said gripping band and adapted to engage the free end of the band after passage through said first named ring to hold the free end connected to said band.
- 30 2. The combination with an ordinary ink receptacle, of a pen rack, including a supporting bar, a flexible attaching band connected to said supporting bar, and adapted for mounting about said ink receptacle for 35 supporting the pen rack therefrom, and a

plurality of resilient friction rings mounted about said gripping band at spaced intervals for gripping engagement with the receptacle.

3. The combination with an ordinary ink 40 receptacle, of a pen rack including a supporting bar, pen supporting means carried by said bar, an attaching band connected to one end of said supporting bar and adapted to be mounted about said ink receptacle for 45 supporting the pen rack therefrom, and a plurality of resilient friction rings adjustably mounted upon said gripping band for gripping engagement with the ink receptacle.

4. The combination, with an ordinary ink receptacle, of a pen rack including a plurality of convolutions of resilient wire, a supporting bar attached to the lowermost portions of said convolutions, a flexible attaching band connected to one end of said supporting bar, a ring carried by one end of said band and adapted to receive the other end of the band therethrough whereby the band may be drawn tightly about said ink 60 receptacle for supporting the pen rack therefrom, and a plurality of resilient friction rings mounted about said gripping band at spaced intervals, for gripping engagement with the ink receptacle, one of friction rings 65 adapted to engage the free end of the band after passing through said ring to hold it connected to said band.

DAVID W. BENTON.
